Primary Examiner — Mary Ann Calabrese(74) *Attorney, Agent, or Firm* — James R. Cypher; Charles R. Cypher**CLAIM**

The ornamental design for an edge lit magnetic sign, as shown and described.

DESCRIPTION

FIG. 1 is an upper right, front perspective view of the edge lit magnetic sign showing my new design.

FIG. 2 is a front elevation view of the edge lit magnetic sign of FIG. 1.

FIG. 3 is a left side elevation view of the edge lit magnetic sign shown in FIG. 1. The right side elevation view of the edge lit magnetic sign is the same.

FIG. 4 is a back elevation view of the edge lit magnetic sign showing my new design.

FIG. 5 is a top plan view of the edge lit magnetic sign of FIG. 1; and,

FIG. 6 is a bottom plan view of the edge lit magnetic sign showing my new design.

The electrical wiring, switch and power supply for the edge lit magnetic sign are shown in broken lines in FIG. 1 for environmental purposes only and form no part of claimed design. Stands for the edge lit magnetic sign are shown in FIGS. 1, 2, 3 and 5 in broken lines for environmental purposes only and form no part of the claimed design. The word logo shown in FIGS. 1, 2 and 4 in broken lines are for environmental purposes only and form no part of the claimed design.
